UNITED STATES PATENT OFFICE.

HENRY L. PITMAN, OF EAST ORANGE, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,356,886.

Specification of Letters Patent. Patented Oct. 26, 1920.

Application filed March 1, 1918. Serial No. 218,771.

To all whom it may concern:

Be it known that I, HENRY L. PITMAN, a citizen of the United States, residing in East Orange, in the county of Essex and State of New Jersey, have invented certain new and useful Improvements in Combined Typewriting and Computing Machines, of which the following is a specification.

This invention relates to typewriting machines having computing mechanisms applied thereto, and particularly to machines in which a master wheel is controlled by the numeral keys of the typewriter, and operates the computing wheels one by one at the typing operation.

The invention is illustrated in connection with the well-known Underwood Addendagraph, in which the key-operated master wheel is mounted upon the stationary frame-work of the machine, while the computing wheels are mounted upon the typewriter carriage.

In manufacturing machines of this style, it is customary to fit the various parts of the computing mechanism upon the previously completed typewriting machine, and to make certain alterations in the typewriting machine.

It is usually necessary to secure very exact coöperation between the master wheel and each of the computing wheels; and this result is found in practice to be difficult and expensive to attain, partly because typewriting machines are not usually manufactured with that extremely high degree of accuracy which is necessary in a key-driven computing mechanism, and partly because the length of the typewriter carriage, in a machine of this class, is usually very great, and the longer the carriage, the more difficult it is to effect satisfactory fitting and co-operation of the master wheel with the computing wheels. The computing wheels are usually assembled in groups, each group having a separate mounting to form a separate totalizer, and each totalizer being usually adjustable to any position along the carriage, so that the range of carriage travel, which must conform to the requirement of accurate fitting, is very great.

In said Underwood Addendagraph, it is the practice to form the typewriter carriage with a front vertical plate, and to support said plate by means of ball or roller bear-

ings upon a track-bar which is fixed upon the machine frame, and which comprises upper and lower grooved rails, between which said carriage plate is arranged, said plate having complementary ball-grooves upon its top and bottom edges; and for the purpose of securing the necessary leveling of the track and also the necessary accurate fitting throughout their length of the grooved rails which form the track, it is customary to make said track-bar in upper and lower parts, each part having one of the grooves, and also to provide for very fine adjustment of the upper and lower rails relatively to each other throughout their length. This adjustment requires a higher degree of skill, and consumes much time, and is otherwise expensive.

The main feature of the present invention is to reduce the cost of fitting and adjustment of said front carriage-track.

I so form the track that the carriage plate which travels thereon will loosely fit along said track, except near that portion thereof which is in the vicinity of the master wheel and carry-over mechanism, at which portion the totalizer will be rigidly held against play.

In producing the track, according to the present improvements, the entire track may be made integral, or at least it may be made with its end portions unadjustable up and down. The middle portion of the track is slotted for a substantial portion of the length of the track, and at this slotted portion provision is made for fine up-and-down adjustments of the grooved rails relatively to each other.

In other words, the track is made adjustable by an aperture or slot extending over a portion of its length in the vicinity of the usual master wheel and carry-over mechanism, so as to make said track slightly flexible or bendable at the portion over which said slot extends. The track at this portion is provided with adjusting mechanisms, whereby it may be expanded or contracted, so that the distance between the grooves or rails thereof may be increased or diminished, so that said rails may lie in closer proximity to the grooved carriage plate at this adjustable portion than at the other portions. The arrangement of ball-bearings is such that a number of bearings will at all times

lie within said adjustable rail portion, co-acting to hold the totalizers against displacement.

Since in this type of machine the master wheel and adjacent actuating mechanism are located centrally of the machine, the track is made adjustable only at the central portion thereof. No computing action takes place on any totalizer when it is at either 10 end of the track. It is, therefore, unnecessary to incur the difficulty and expense of providing fine adjustments or accurate movement of the parts at the ends of the track.

15 The end portions of the track are therefore never accurately fitted, but permanently remain a trifle over-separated. In fact, as the track is originally made, the grooves or rails throughout their length are a trifle 20 over-separated, so that no attempt is made to secure, at the track-milling operation, any fine degree of accuracy, whereby expense is reduced. Then the adjusting screws are brought into play to cause the central portions of the rails to approach each other, 25 until the desired accuracy is secured at this portion.

The trifling play or looseness at the end 30 portions of the track is found not to be objectionable, since the ball-bearings are so spaced and so placed with relation to the split and accurately-adjusted portion of the track that no shake or play occurs at the point where the master wheel is operating 35 upon a totalizer, regardless of where said totalizer is placed along the carriage.

Hence, the track with its grooves may be 40 made in one piece; the grooves are inexpensively milled therein to allow play throughout the travel of the carriage, and then the split portion of the track is adjusted to take up such play, so that there 45 is no appreciable play at the point where the master wheel is operating upon the computing wheels at any time. Thus, such accuracy of operation as is necessary is secured, but at a much less expense than by the usual method.

50 Preferably one of the rails of said track is made to bear a fixed relation to its base, and the opposed rail is made adjustable in the vicinity of the master wheel. The master wheel and adjacent actuating mechanism are mounted in fixed relation to said 55 fixed rail, so as to be in proper meshing relation with the wheels of the totalizer and still permit adjustments of the track relatively to the bearings therebetween and the carriage plate on which the totalizers 60 are mounted.

Other features and advantages will hereinafter appear.

In the accompanying drawings.

Figure 1 is a part-sectional front view, 65 showing a portion of the Underwood Ad-

dendograph with the invention applied thereto, the position of the bearings being indicated when the carriage is near its central position.

Fig. 2 is a side view of a portion of the 70 Underwood Addendograph, showing the front rail, on which the carriage and totalizers travel, in section at its adjustable portion.

Fig. 3 is a diagrammatic sectional view 75 taken on the line 3—3 of Fig. 1, when the carriage is at the extreme end of its rightward travel, showing one group of bearings within the adjustable portion of the rail and one group without said adjustable portion. 80

Numeral keys (not shown) actuate type-bars 10, Fig. 2, to strike against a platen 11, mounted on a typewriter carriage 12, slidably mounted on a bar 13 at the rear of the machine and a track 14 at the front of the machine. The carriage is provided with the usual escapement mechanism controlled by the keys, and is driven by a spring barrel (not shown). One or more totalizers 15. 90 Figs. 1, 2 and 3, are adjustably mounted on a plate 16, which forms part of the carriage 12.

To rotate the computing wheels 17, Fig. 2, of the totalizer at the actuation of the 95 numeral keys, there is provided an actuating mechanism, indicated in general at 18, including a master wheel 19 and adjacent carry-over mechanism 20, which is usually mounted at the central portion of the machine in front of and below said track 14. The wheels 19, 20 of said actuating mechanism are connected to the numeral keys to rotate the computing wheels in accord with the digital value of any numeral key actuated, said rotation being imparted to the 100 wheels 17 of any totalizer 15 when said totalizer is in a computing zone, Figs. 2 and 3, that is, when its wheels are in juxtaposition with the master wheel 19 and 105 wheels of the carry-over mechanism 20.

To secure accuracy of co-operation between the totalizer wheels 17 and the master wheel 19 and carry-over wheels 20, and to hold said totalizer 15 rigidly during the 115 computing action, the latter is positively guided and held against displacement, beginning preferably just prior to its entrance into a computing zone before its wheel 17 of highest denomination meshes with the 120 master wheel 19, and continuing for a short distance after its wheel 17 of lowest denomination passes the wheels of the carry-over mechanism 20.

For this purpose, the front track 14, 125 Figs. 1 and 2, is rigidly supported at its ends 22 by brackets 23 fast to the sides of the framework 24 of the machine, and that portion of the track 14 which lies near and within the computing zone or near the 130

master wheel is provided with means for adjusting the track. The track 14 includes horizontally-disposed upper and lower rails 25, 26, respectively, formed integrally with 5 a common base or plate 27, which has an aperture or slot 28 formed at its central upper portion 29, Fig. 1, near the central portion 30 of the upper rail 25. Said rail is in the form of a groove or channel forming 10 bearing surfaces 31, Fig. 2, which are arranged in an opposed or complementary manner to similar bearing surfaces 32 formed on the lower rail 26 of said track. The bearing surfaces 31, 32 are in the form 15 of V-grooves to receive balls or rolls 36. The normal distance between the rails 25, 26 of the track 14 is such that said front plate 16, which runs on ball bearings or preferably on roller bearings along said 20 track will fit loosely between the rails of said track, so as to allow considerable play or lost-motion between said bearings and the bearing surfaces 31, 32, Fig. 2, formed on the track and the bearing surfaces 33, 25 34 formed on opposed bars or rails 35 of the plate 16 on which the totalizers are mounted.

The track 14 is provided with an adjusting mechanism, Fig. 1, in the form 30 of expanding and contracting devices located at the central portion 29 of the track to increase or diminish the distance between the rails 25, 26 at said central portion.

35 For forcing the upper rail 25 away from the lower rail 26, there are provided expansion screws 37, Fig. 1. Said screws are threaded through the flexible portion of the track near the central portion 30 of the upper rail 25, with their ends abutting against the rigid fixed portion of the rail base 27. If said screws are turned inwardly, their ends abutting against said fixed portion will cause the upper rail 25 to spring 40 or move away from the lower rail 26, thereby increasing the distance between said rails. If said screws are turned outwardly, the upper rail portion 30 will spring or return to its normal position.

50 To diminish the distance between the rails 25, 26 and 35, contraction screws 38, Fig. 1, are oppositely arranged relatively to the expansion screws 37, and pass loosely through said flexible portion of the track 55 14, and are threaded into the fixed portion of said rail base 27. Said contraction screws 38 are so arranged that when turned inwardly, the lower surface of their heads will bear down on the central portion 30 of the upper rail 25, thereby moving said rail into closer proximity with its opposed lower rail 26 and the rails 35 on the front plate 16 carrying the totalizers, thereby diminishing the distance between the rails and the amount

of lost-motion therebetween and the bearings 36. 65

It will be noted that the expansion and contraction screws 37 and 38, respectively, pass through the slot 28, Fig. 1, provided in the base 27 of the track 14. It will 70 also be noted that in the use of said screws, the contraction screws 38 may be loosened prior to the manipulation of the expansion screws 37, and vice versa; and that when the desired adjustment is effected, those 75 screws which have been employed to effect said adjustment are tightened, thereby locking the parts in their adjusted positions. It will also be noted that by the manipulation of said screws the cross-sectional area of 80 the raceways may be varied at the adjustable rail portion 29 while said area at other rail portions remains constant.

By employing rail-adjusting means, as herein described, there will be no break in 85 the continuity of the bearing surfaces of the rails 25 and 26 in any of the several adjusted positions.

It will be seen, by reference to Fig. 1, that the opposed rails 25 and 26, along that portion lying between the contraction screws 38, are substantially equidistant, and that the rail 25 is tapered from a point about where said contraction screws 38 are located, to a point about where the slot 28 in said 90 track 14 ends, as at 39. These tapered rail portions 39 are flexible and serve to connect the adjustable rail portion 30 with the fixed rail portions. 95

Since the bearings 36 run within the track 100 14 in this embodiment of the invention, it is desirable that the track contraction mechanism shall include a greater part of said adjustable track portion 29.

For this purpose, the contraction screws 105 38, Fig. 1, are placed nearer the ends of the slot 28 than the expansion screws 37, thereby placing within the control of the screws 38 a greater length of rail portion 30 than controlled by the expansion screw 37, and 110 thereby minimizing the length of the tapered portions 39 of said rail 25.

The bearings 36 are mounted in cages 40, one for the bearings running on the upper rails 25 and 35, and one for the bearings 115 running on the lower rails 26 and 35, and are so placed on said rails as to run in unison laterally along the track 14, a distance of half a letter-space for every letter-space movement of the typewriter carriage 12 and 120 plate 16 on which the totalizers 15 are mounted, and in the same direction. The bearings 36 are so placed on the rails as to lie centrally on the track 14 when the typewriter carriage 12 is in its central position. The invention is not limited to the use of balls or rolls which travel at half the speed of the carriage. 125

It will be seen, by reference to Figs. 1 and 3, that the bearings 36 on which the front plate 16 travels along the track are so arranged that a plurality of said bearings 36 always lie within the adjustable portion 29 of the track, said adjustable portion being of such extent relative to the lateral distance between the end bearings as to effect this condition. In other words, when the typewriter carriage 12 and connected parts are centrally positioned, as approximately and diagrammatically shown in Fig. 1, all the bearings 36 will lie within the adjusted portion 29 of the track 14 and on each side of the actuating mechanism 18, thereby holding the totalizer 15 juxtaposed on said actuating mechanism against vertical displacement. When said carriage is moved to the extreme end of its travel, one group of bearings 36 will lie snugly within the adjusted portion 29 of the rail near the actuating mechanism 18, thereby holding the juxtaposed totalizer against displacement, even though other portions of the plate 16, on which said totalizers are mounted, may be loose on the bearings.

It will be seen that with this arrangement, as one group of bearings 36 leaves the adjustable rail portion 29 when the carriage 12 travels laterally, another group of bearings 36 rolls into said adjustable portion before the first group is without the adjustable portion, so that a group of bearings 36 will at all times lie within said adjusted rail portion 29 when the carriage 12 is at any of its several positions between the extreme ends of its travel.

The adjusting means, herein disclosed, may also be used for correcting inaccuracies in the distance between the rails of the track 14.

It will be noted that the parts wear mostly along the adjustable portion 29 of the rail, since there is less lost-motion between said parts within said portion than at other portions, the parts being loosely mounted within said other portions. The small amount of wear occurring on said other portions, during the long continued use of the machine, will not prove objectionable.

If, however, the lower rail 26 should become excessively worn, so that the computing wheels 17 of the totalizer should lie too close to the master wheel 19 and carry-over wheels 20, the rail may be bodily raised on the supporting brackets 23; adjustment for this purpose also being provided at the point as at 41, Fig. 1, where the master wheel and adjacent mechanism are attached to the track.

The track 14 may be economically produced, and with less accuracy than that usually required. The opposed rails 25, 26, having V-grooves, or other contour, may be milled simultaneously and equidistantly

throughout the entire length of the track. Then the holes may be drilled and threaded for the adjusting screws 37, 38. Thus far the track 14 is rigid throughout, and cutting operations may be performed with certainty. After the above cutting operations are performed, the aperture or slot 28, which gives the rail its flexibility, may be cut. The track, therefore, will not spring under the strain of the cutting operations.

The roller bearings 36, or other form of bearings, need not be formed with as great care and accuracy as heretofore. It is only essential that the bearings 36 in a set shall be of equal dimensions. Other sets of bearings 36 may be employed of different dimensions within the capacity of the track 14 at its fixed portions, the adjustable portion 29 being set in accord with the dimensions of the bearings 36 and the distance between the rails of the track 14 and the plate 16 on which the totalizers are mounted, and on which said bearings 36 run. When worn or broken bearings are being replaced, it is not essential that the new bearings shall be of exactly the same dimensions as the old ones.

It will also be seen that the plate 16, along which the totalizers are mounted, need not be accurately formed with respect to the distance between its bars 35, because of the adjustability of the track 14. This avoids undue expense in the production of said plate 16.

Variations may be resorted to within the scope of the invention, and portions of the improvements may be used without others.

Having thus described my invention, I claim:

1. In a combined typewriting and computing machine, the combination with a traveling carriage, of a track on which it travels, a totalizer, a master wheel, two rails fixedly connected throughout certain portions by a base, forming said track, a plate on said carriage on which said totalizer is mounted, said plate running on said track, and means for adjusting said track, in a portion of its length relatively to the plate.

2. In a combined typewriting and computing machine, the combination with a traveling carriage, of a track on which it travels, a totalizer, a master wheel, two rails fixedly connected throughout certain portions by a base, forming said track, a plate on said carriage on which said totalizer is mounted, said plate running on said track, and means for adjusting said track, in a portion of its length relatively to the plate, said means including track-adjusting mechanisms.

3. In a combined typewriting and computing machine, the combination with a traveling carriage, of a track on which it travels, a totalizer, a master wheel, two rails

connected by a base forming said track, a plate on said carriage on which said totalizer is mounted, said plate running on said track, and means for adjusting a portion of 5 said track relatively to the plate, said means including a track-contracting mechanism and a track-expanding mechanism.

4. In a combined typewriting and computing machine, the combination with a 10 traveling carriage, of a track on which it travels, a totalizer, a master wheel, two rails fixedly connected throughout certain portions by a base, forming said track, a plate on said carriage on which said totalizer is 15 mounted, said plate running on said track, and means for adjusting said track, in a portion of its length relatively to the plate, said means being adapted to hold said track in adjusted position.

20 5. In a combined typewriting and computing machine, the combination with a totalizer, of a master mechanism, a totalizer carriage including a plate having V-grooves facing in opposite directions, plate-guiding 25 means including an integral track-plate having V-grooves facing those of the carriage-plate, means for adjusting relatively to each other the grooved portions of said track-plate along an intermediate portion of its 30 length, and means for supporting said track-plate in different adjusted positions.

6. In a combined typewriting and computing machine, the combination with a 35 totalizer, of a master mechanism, a totalizer carriage including a plate having V-grooves facing in opposite directions, plate-guiding means including an integral track-plate having V-grooves facing those of the carriage-plate, said track-plate having a longitudinal 40 slot near its upper grooved portion and extending along an intermediate portion of the track-plate, and means to adjust the position of the upper grooved portion of the track-plate with reference to the lower in the 45 vicinity of the slot, said adjusting means including a plurality of screws for drawing the upper grooved portion toward the lower and a plurality of screws for forcing it away.

50 7. In a combined typewriting and computing machine, the combination with a traveling carriage, of a track mounted on the frame of the machine, a plate on said carriage extending in front of said track, 55 bearings between said plate and said track, said track including two bearing-surfaces integral with a common base, and means for varying the distance between only a portion of said bearing-surfaces.

60 8. In a combined typewriting and computing machine, the combination with a traveling carriage, of a totalizer, a plate on said carriage for mounting said totalizer, and a track on which said plate and totalizer 65 travel, said track being formed integrally

and having an aperture and adjusting devices thereon for adjusting it relatively to the totalizer.

9. In a combined typewriting and computing machine, the combination with a 70 traveling carriage, of a totalizer, a master wheel coöperating with said totalizer, a plate on said carriage on which said totalizer is mounted, and a track on which said plate and totalizer travel, said track having 75 a rigid portion near said master wheel and an opposite resilient portion.

10. In a combined typewriting and computing machine, the combination with a traveling carriage, of a totalizer, a master 80 wheel coöperating with said totalizer, a plate on said carriage on which said totalizer is mounted, and a track on which said plate and totalizer travel, said track having 85 a rigid central portion and an opposite re- silient central portion.

11. In a combined typewriting and computing machine, the combination with a traveling carriage, of a totalizer, a master 90 wheel coöperating with said totalizer, a plate on said carriage for mounting said totalizer, and a track on which said plate and totalizer travel, said track including 95 relatively-adjustable rails integral with a common base. 95

12. In a combined typewriting and computing machine, the combination with a traveling carriage, of a totalizer, a master wheel coöperating with said totalizer, a plate on said carriage for mounting said 100 totalizer, a track on which said plate and totalizer travel, said track including relatively-adjustable rails integral with a common base, and adjusting devices mounted on 105 said base.

13. In a combined typewriting and computing machine, the combination with a traveling carriage, of a totalizer, a master wheel coöperating with said totalizer, a plate on said carriage for mounting said 110 totalizer, and a track on which said plate and totalizer travel, said track having fixed and adjustable portions arranged in succession longitudinally of said track. 110

14. In a combined typewriting and computing machine, the combination with a traveling carriage, of a totalizer, an actuating mechanism coöperating with said totalizer, a plate on said carriage for mounting the totalizer, and a track on which said 115 plate and totalizer travel, said track having 120 fixed end portions and an adjustable central portion near the actuating mechanism.

15. In a combined typewriting and computing machine, the combination with a 125 traveling carriage, of a totalizer, a master wheel coöperating with said totalizer, a plate on said carriage for mounting said totalizer, and a track on which said plate and totalizer travel, said track having a 130

fixed lower rail and a centrally adjustable upper rail having its ends fixed.

16. In a combined typewriting and computing machine, the combination with a traveling carriage, of a totalizer, an actuating mechanism coöperating with said totalizer, a plate on said carriage for mounting said totalizer, and a track on which said plate and totalizer travel, said track including a rail having a fixed portion opposite the actuating mechanism, and a rail having fixed end portions and an adjustable portion opposite the fixed portion of the first mentioned rail near said actuating mechanism.

17. In a combined typewriting and computing machine, the combination with a totalizer, of a master wheel, a totalizer carriage, and a track for said totalizer carriage, comprising two rails, connecting means whereby said rails are held fixed relatively to each other throughout the greater part of their length, but are permitted to have relative movement in the vicinity of said master wheel, and means to effect relative adjustment of the rails in the vicinity of said master wheel, to obtain proper positioning of said totalizer carriage with reference to said master wheel.

18. In a combined typewriting and computing machine, the combination with a traveling carriage, of a totalizer, a master wheel coöperating with said totalizer, a plate on said carriage for mounting said totalizer, and a track on which said plate and totalizer travel, said track including two rails, one of which is fixed at both ends and centrally adjustable.

19. In a combined typewriting and computing machine, the combination with a traveling carriage, of a track on which it travels, a totalizer, a master wheel, two rails rigidly connected at each side of said master wheel by a common base forming said track, a plate on said carriage on which said totalizer is mounted, said plate running on said track, and means for varying the distance between said rails at the central portion of said track.

20. In a combined typewriting and computing machine, the combination with a traveling carriage, of a track on which it travels, a totalizer, a master wheel, two rails rigidly connected at their end portions by a common base forming said track, a plate on said carriage on which said totalizer is mounted, said plate running on said track, and a plurality of screws for varying the distance between said rails at the central portion of said track.

21. In a combined typewriting and computing machine, the combination with a traveling carriage, of a track on which it travels, a totalizer, a master wheel, two

rails rigidly connected at their end portions by a common base forming said track, a plate on said carriage on which said totalizer is mounted, said plate running on said track, a plurality of screws for increasing the distance between said rails in their central portions, and a plurality of screws for diminishing the distance between said rails in their central portions.

22. In a combined typewriting and computing machine, the combination with a totalizer, of a master mechanism, a totalizer carriage, and a totalizer-carriage track, comprising two rails connected by plates, one on each side of said master mechanism, integral therewith, but disconnected opposite said master mechanism, and means to effect relative adjustment of said rails in the vicinity of said master mechanism, in order to obtain an accurate positioning of said totalizer with reference to said master mechanism in passing the same.

23. In a combined typewriting and computing machine, the combination with a totalizer, of a master wheel, a totalizer-carrying plate, and a plate-guiding means including a track, comprising two rails, and means for moving portions of said rails toward and from each other and to retain the same in adjusted position.

24. In a combined typewriting and computing machine, the combination with a traveling carriage, of a plate on said carriage traveling therewith, a totalizer adjustable along said plate and adapted to travel therewith over a master wheel, and a track on which said carriage and plate travel, said track rigidly holding said totalizer when in a computing zone, and loosely holding said totalizer when out of a computing zone.

25. In a combined typewriting and computing machine, the combination with a traveling carriage, of a plate on said carriage traveling therewith, a track along which said plate and carriage travel having successive adjustable and rigid portions arranged longitudinally thereof, and bearings on said plate traveling along said track, one or more of said bearings lying within said adjustable track portion in any position of said plate along said track.

26. In a combined typewriting and computing machine, the combination with a traveling carriage, of a plate on said carriage traveling therewith, a totalizer adjustably mounted on said plate, a track having successive adjustable and fixed portions, arranged longitudinally thereof, along which said plate, carriage and totalizer travel, a master wheel mounted near said adjustable track portion, and bearings traveling between said plate and track, said bearings being so arranged that one or more

of said bearings lie within said adjustable track portion when said totalizer is in juxtaposition with the master wheel.

27. In a combined typewriting and computing machine, the combination with a traveling carriage, of a plate on said carriage traveling therewith, a totalizer on said plate, a master wheel for actuating said totalizer, and a track including a fixed rail 10 and a rail having an adjustable portion and fixed portions, said master wheel being attached to said fixed rail at a point opposite said adjustable rail portion.

28. In a combined typewriting and computing machine, the combination with a traveling carriage, of a plate on said carriage traveling therewith, a track on which said carriage and plate travel, a master wheel bearing a fixed relation to a portion 20 of said track, carry-over mechanism bearing a fixed relation to a portion of said track, a totalizer adjustable along said plate and traveling therewith over the master wheel and over said carry-over mechanism, 25 and means for adjusting another portion of said track relatively to the master wheel and carry-over mechanism to maintain a substantially fixed relation between the totalizer and the master wheel and carry-over 30 mechanism at any position of the totalizer along said plate.

29. In a combined typewriting and computing machine, the combination with a traveling carriage, of a plate on said carriage traveling therewith, a totalizer adjustably mounted on said plate, a track having adjustable and rigid portions along which the plate, carriage and totalizer travel, a master wheel mounted near said 40 adjustable track portion, carry-over mechanism mounted near the adjustable track portion, and bearings traveling between the plate and track, said bearings being so arranged that one or more bearings lie 45 within said adjustable track portion when said totalizer is in juxtaposition with the master wheel and with the carry-over mechanism.

30. In a combined typewriting and computing machine, the combination with a traveling carriage, of a plate on said carriage traveling therewith, a totalizer adjustably mounted on said plate, a track having adjustable and fixed portions along which 55 said plate, carriage and totalizer travel, carry-over mechanism mounted near the adjustable track portion, and bearings traveling between said plate and track, said bearings being so arranged that one or more 60 bearings lie within the adjustable track portion when said totalizer is in juxtaposition with the carry-over mechanism.

31. In a combined typewriting and computing machine, the combination with a traveling carriage, of a plate on said car-

riage traveling therewith, a totalizer on said plate, a master wheel for actuating said totalizer, carry-over mechanism cooperating with said totalizer, a fixed rail over which said plate and totalizer travel, and a rail 70 having an adjustable portion, said master wheel and carry-over mechanism being attached to said fixed rail opposite said adjustable rail portion.

32. In a combined typewriting and computing machine, the combination with a traveling carriage, of a totalizer on said carriage movable into and out of a computing zone, and a track including rails on which said carriage and totalizer travel, said 80 rails being in closer proximity at the computing zone than at other points along the track.

33. In a combined typewriting and computing machine, the combination with a 85 traveling carriage, of a totalizer on said carriage movable into and out of a computing zone, and a track including rails on which said carriage and totalizer travel, said rails being differently spaced at the central portion of the track than at other points along the track.

34. In a combined typewriting and computing machine, the combination with a traveling carriage, of a totalizer on said carriage movable into and out of a computing zone, and a track including rails on which said carriage and totalizer travel, said rails being differently spaced at the computing zone than at other points along the track. 100

35. In a combined typewriting and computing machine, the combination with a traveling carriage, of a plate including rails on said carriage, a totalizer movable into and out of a computing zone mounted on 105 said plate, a track including rails on which said plate and totalizer travel, and bearings between said plate-rails and track-rails, said track being so arranged that the rails are in closer proximity to said bearings at the computing zone than at other points along the track-plate. 110

36. In a combined typewriting and computing machine, the combination with a traveling carriage, of a plate on said carriage traveling therewith, a totalizer adjustable along said plate and adapted to travel therewith over a master wheel, said totalizer including computing wheels, and a track on which said carriage and plate travel, said 115 track rigidly holding the computing wheels in mesh with the master wheel when the latter are driven by said master wheel, and loosely holding them when out of range with respect to said master wheel. 120

37. In a combined typewriting and computing machine, the combination with a traveling carriage, of a platen mounted on said carriage including a plurality of computing zones, a totalizer on said carriage 130

- traveling therewith, actuating mechanism coöperating with said totalizer, a track along which said carriage and totalizer travel, said track having a fixed portion and the portion near said actuating mechanism adjustable, and means for adjusting said track portion to hold the totalizer against displacement when computing in any of said zones.
38. In a combined typewriting and computing machine, the combination with a traveling carriage, of a plate on said carriage having opposed V-grooves formed thereon, a track having successive adjustable and fixed portions, arranged longitudinally thereof, along which said plate travels, said track having V-grooves formed thereon opposed to the V-grooves on said plate, the V-grooves forming race-ways of rectangular contour, bearings running in said race-ways, a totalizer mounted on said plate and traveling therewith, actuating mechanism coöperating with said totalizer, and means for varying the cross-sectional area of said race-ways at said adjustable track portion.
39. In a combined typewriting and computing machine, the combination with a traveling carriage, of a plate on said carriage having opposed V-grooves formed thereon, a track having adjustable and fixed portions, arranged in succession longitudinally thereof, along which said plate travels, said track having V-grooves formed thereon opposed to the V-grooves on said plate, the V-grooves forming race-ways of rectangular contour, bearings running in said race-ways, a totalizer mounted on said plate and traveling therewith, actuating mechanism coöperating with said totalizer, and means for varying the cross-sectional area of said race-ways at said adjustable track portion.
40. In a combined typewriting and computing machine, the combination with a traveling carriage, of a track having adjustable and fixed portions, arranged in succession longitudinally thereof, along which said carriage travels, a plate on said carriage forming a mounting for totalizers and traveling along said track, and actuating mechanism near said adjustable track portion coöperating with said totalizers, said track being adapted to hold said totalizers against vertical displacement when in juxtaposition with said actuating mechanism.
41. In a combined typewriting and computing machine, the combination with a traveling carriage and a plate on said carriage on which totalizers are mounted, of a track along which said plate and totalizers travel, said track having fixed and adjustable portions arranged in succession longitudinally thereof, and a master wheel and carry-over wheels coöperating with said totalizers, said wheels and said adjustable track portion being attached to a common support, said adjustable portion extending laterally beyond the master wheel and any of the carry-over wheels.
42. In a combined typewriting and computing machine, the combination with a traveling carriage and a track along which it travels, of fixed track portions, and a track portion, between said fixed portions adjustable to several positions, contiguous with said fixed track portions in any of said several positions.
43. In a combined typewriting and computing machine, the combination with a totalizer, of a master mechanism, a totalizer carriage including a plate having V-grooves facing in opposite directions, plate-guiding means including an integral track-plate having V-grooves facing those of the carriage-plate, and means for adjusting relatively to each other the grooved portions of said track-plate along an intermediate portion of its length.
44. In a combined typewriting and computing machine, the combination with a totalizer, of a master wheel, a totalizer carriage, and carriage-guiding means including a track, comprising rails, means to hold said rails relatively fixed in certain portions of the track, and means to adjust said rails relatively to each other in the vicinity of said master wheel.
45. In a combined typewriting and computing machine, the combination with a traveling carriage, of a track comprising a rail along which the carriage travels, a rail portion opposite each end portion of said rail and fixed thereto, and a rail portion opposite the central portion of said rail and adjustable with respect thereto.
46. In a combined typewriting and computing machine, the combination with a totalizer, of a master wheel, a totalizer-carrying plate, and plate-guiding means including a track, comprising two rails, and a common base integral therewith and having provisions whereby the distance between said rails in the vicinity of said master wheel may be varied.

HENRY L. PITMAN.
